UNITED STATES PATENT OFFICE.

WILLIAM MCCLAVE, OF SCRANTON, PENNSYLVANIA, ASSIGNOR TO MCCLAVE-BROOKS COMPANY, OF SCRANTON, PENNSYLVANIA, A CORPORATION OF PENNSYLVANIA.

FURNACE CONSTRUCTION.

1,318,579.

Specification of Letters Patent.

Patented Oct. 14, 1919.

Application filed December 20, 1916. Serial No. 138,043.

To all whom it may concern:

Be it known that I, WILLIAM MCCLAVE, a citizen of the United States, residing at Scranton, in the county of Lackawanna and 5 State of Pennsylvania, have invented certain new and useful Improvements in Furnace Construction; and I do hereby declare the following to be a full, clear, and exact description of the same, reference being had to 10 the accompanying drawings, forming part of this specification.

This invention relates generally to an improved furnace construction; the primary object in view is to provide a furnace of 15 exceedingly simple construction which is particularly adapted for the burning of bituminous coal, and wherein the fuel may be efficiently and evenly underfed to the grate, either by the use of power rams or 20 hand tools especially designed for this purpose, as the case may require, thereby practically eliminating smoke as a factor in operating the furnace. Features of the invention, however, are applicable to other types 25 of furnaces as well, and it will be understood that the scope of the invention is by no means limited to the specific embodiment herein described and illustrated.

In prior constructions embodying the underfeed principle of stoking, it has been customary to employ fuel hoppers in which the fuel is deposited before being delivered to the grate, by power rams or otherwise. These hoppers necessarily occupy a large 35 space in front of the furnace and are a great inconvenience, because they render access to the combustion chamber or ash pit of the furnace exceedingly difficult, when it becomes necessary to insert a tool for some 40 purpose, such as to ram fuel down the grate. Hence, the use of hoppers in front of the furnace has always been regarded as decidedly disadvantageous, in some instances offsetting the advantages accruing from underfeed 45 stoking, although, in prior constructions for stoking, no practical substitute for hoppers has even been proposed, to my knowledge. A special object of the present invention is to dispense with these hoppers, 50 and to substitute therefor a specially constructed fuel receiving channel within the furnace itself, in combination with means for distributing fuel fed to the channel whereby the fuel may be subsequently underfed to the grate to supply the needs of

the fire. The improved channel will occupy a minimum space in the furnace in front of the fuel receiving end of the grate, and will not prevent the location and use of fire doors in the front of the furnace for permitting 60 access to the combustion chamber when desired.

Other objects of the invention are to generally improve the furnace construction, as will appear from the ensuing detailed description, when taken in connection with the accompanying drawings which illustrate a structural embodiment of the invention in a preferred form. The novel features of the invention will be particularly pointed out 70 and specified in the claims at the end of the specification.

In the drawings:

Figure 1 is a front elevation of a furnace provided with the present improvements, 75 and embodying power operated stoking mechanism.

Fig. 2 is a sectional side elevation of the same.

Fig. 3 is a horizontal section taken in 80 planes indicated by the line 3-3 of Fig. 2.

Fig. 4 is a vertical section on the line 4-4 of Fig. 2.

Fig. 5 is a detail plan view of one of the rams, or pushers hereinafter described. 85

Fig. 6 is an elevation of the ram and its cover plate looking in the direction of the arrow of Fig. 5.

Fig. 7 is a transverse section of the ram and its cover plate, the ram being in section in a plane indicated by the line 7-7 of Fig. 5. 90

Fig. 8 is a transverse section of the ram on the line 8-8 of Fig. 5.

Fig. 9 is a transverse section of the ram 95 on the line 9-9 of Fig. 5.

Fig. 10 is a sectional side elevation similar to Fig. 2, of a furnace not equipped with power operated stoking mechanism, but embodying features of the present invention. 100

Fig. 11 is a front elevation of a furnace illustrating an application of the present improvements to an extra wire furnace, wherein in a plurality of coal delivery chutes are employed. 105

Like characters of reference in the several figures indicate the same parts.

The improvements of the present invention are illustrated in connection with a furnace divided into two divisions or sec- 110

tions, for example, by a pier of brickwork or other refractory material, each division being equipped with a grate, and the two grates are located in a single combustion chamber. It will be obvious that the number of divisions of the furnace is immaterial and may be varied at will, or a furnace equipped with a single grate is equally amenable to the invention. Within the combustion chamber 1 of said furnace are the grates 2, supported preferably in an inclined position therein, as shown more particularly in Fig. 2. The upper fuel-receiving ends of the said grates are supported by the lower girder member 3 of a double transverse bearing bar, the upper girder member 4 of said bar being utilized in a manner which will hereinafter appear. The bearing bar extends clear across the combustion chamber and is supported by the side walls of the latter in any manner well known in the art. The lower end of the inclined grate may be supported in any suitable manner, and at said lower end, there is arranged a rocking section 5 preferably journaled to oscillate in bearings formed in bearer bars bridged between the lower end of the grate and the forward member 6 of a series of transverse girders or beams, supporting the rear wall 8 of the combustion chamber. In its preferred construction the rocking section 5 is composed of rearwardly-extending fuel supporting and dumping extensions and forwardly extending segmental sections. The movement of the rocking section of each grate is controlled by an operating bar or link 9 pivoted to a downwardly extending arm 10 of the rocking section, and extending out through the front wall of the furnace, where said link is pivoted to a suitable operating lever arm 11 located outside the front furnace wall.

Beneath the grate, the bottom of the combustion chamber is extended by means of downwardly inclined flooring sections 12 and 13 to form an ash pit 14 into which the fire may be dumped, as required. The furnace illustrated is particularly adapted for the burning of bituminous coal in thick heavy beds or other coal of like consistency, and, therefore, it is desirable that an artificial draft may be supplied beneath the grate by an inlet 15 at the bottom of the ash pit.

Aside from certain novel details, which will be hereinafter set forth, the main feature of my invention lies in the transverse fuel-receiving channel from which fuel can be efficiently underfed to the grate, or grates, either by power rams, or hand tools, especially designed for this purpose, as circumstances may require. The present construction dispenses altogether with the use of hoppers, and enables the proper location and use of fire doors, while at the same time pro-

viding an efficient underfeed and practically eliminating smoke as a factor in the operation of the furnace.

In the embodiment of the invention illustrated in Figs. 1 to 9, inclusive, power operated rams are employed for the purpose of pushing the fuel from channels on to the grates. The fuel receiving channels 16 are located at the forward end of the furnace directly behind the front wall 17 of the furnace, there being a channel for each grate 2, respectively located on opposite sides of the dividing pier 18. The bottom of each channel 16 is formed by a lower dead plate 19 supported by triangular bearing members 20 extending inwardly from the rear face of the front wall 17, as shown more particularly in Fig. 2. To insure great rigidity and strength the innermost angular portions 20^a of the several bearing members 20 are bolted to the forward girder member 4 of the transverse grate bearer bar, hereinbefore referred to. According to the present embodiment, it is intended that the two channels 16 be supplied with fuel from a common source, and, therefore, their proximate ends are bridged by a plate 21, thereby forming a practically continuous surface or passage way within the furnace on which fuel is spread out or distributed. The outer ends of the channels are inclosed by the side walls 22 of the furnace proper, and from above they are inclosed by the upper dead plate 23 (see Fig. 4). Said dead plate 23 is supported in front by the front wall 17 of the furnace and in the rear upon an inner wall or plate 24. Both the upper dead plate 23 and the inner wall 24 extend transversely substantially clear across the front of the furnace.

Above the center plate 21 the upper dead plate 23 is provided with a fuel inlet 25 which communicates with the lower end of a vertical fuel delivery chute 26, the latter extending between the two vertical division plates 27. The chute 26 leads to the coal bunkers, and, as shown in Fig. 2, curves outwardly from the furnace, but the shape of the chute is dependent entirely upon the location of the coal bunkers. Coal falls through the chute 26 by gravity and is deposited upon the center plate 21. As the channels 16 extend clear across the fuel receiving end of each grate 2, it is essential that some means be provided for distributing the fuel transversely along the channels, so that it can be subsequently fed to the grate. For this purpose, a sweep or plate 28 is pivoted by a stub shaft 29 in the space above the plate 21, and is intended to divide the coal as it is discharged by the chute and by a swinging movement push coal first into one channel 16 and next into the other channel. The stub shaft 29 extends through the front wall 17 of the fur-

nace and is provided at its outer end with a gear segment 30 (see Fig. 1). In mesh with said gear segment is a rack 31 carried by a block 32 which is adapted to be reciprocated in a slideway 33 and swing the gear segment 30, thereby imparting a swinging movement to the sweep 28.

For operating the block 32, connections are provided between said block and a main power shaft 34 which is journaled in bearings in the front of the furnace. According to this invention the said operating connections are so constructed, that the shaft 34 will be rotated without interference, when the coal packs against the sweep either on one or both sides of the latter so as to preclude movement of the sweep in either or both directions. In other words, when the pressure of the coal on the sweep becomes great enough so as to interfere with its movement, the sweep will be permitted to remain stationary, while the main shaft rotates, without transmitting any stress to the main shaft. For accomplishing this result a connection is interposed between the sweep and the shaft, which is adapted to yield under pressure of the coal on either one or both sides of the sweep, as will now be described. Secured to the main power shaft 34 is a crank 35 to which is pivoted the lower end of a rod 36. The rod 36 is integral or otherwise rigidly connected with a hollow cylinder 37 and adapted to work within the latter is a rod 38 pivoted at its upper end to the reciprocating block 32 and furnished at its lower end within the cylinder with a head 39. Beneath the head 39 in the cylinder 37 is a coil spring 40, and above the head 39 is a second coil spring 41 encircling the rod 38 and bearing on the upper end of the cylinder 37, as shown in Fig. 1. The two springs are of equal size and tension and their combined tension on the head 39 maintains the latter in a position substantially midway between the upper and lower ends of the cylinder 37. The springs 40, 41 are also strong enough to transmit reciprocating motion imparted to the rod 36 and cylinder 37 to the upper rod 38, under normal conditions, *i. e.* before the channels 16 are packed with coal, and when the latter is being pushed without the formation of excessive pressure into the channels, for subsequent distribution to the grates 2. Under these conditions the motion of the shaft 34 is transmitted to the block 32, which is reciprocated, and thereby imparts a swinging movement to the sweep 28, the latter pushing coal discharged from the chute along first into one channel 16 and then into the other.

If, however, one channel should pack sooner than the other, movement of the sweep would be retarded or even entirely prevented in the direction of that channel.

Assuming that the right hand channel illustrated in Fig. 4 is packed with coal and that the left hand channel has not yet been filled, movement of the sweep toward the right could not be effected although the sweep 28 could swing toward the left to push the coal along into the left hand channel. It will be noted that upward movement of the cylinder 37 and rod 38 swings the sweep 28 toward the left and lowering movement of the rod and cylinder swings the sweep toward the right. Under the above stated conditions, no undue resistance will be offered to upward movement of the rod 38, and consequently swinging movement of the sweep to fill the left hand channel will not in any way be affected by packing of the right hand channel, the two springs retaining their normal positions throughout the up-stroke of the several parts of the apparatus. During lowering movement of the cylinder, however, swinging movement of the sweep 28 toward the right is resisted by the coal packed within the right hand channel and consequently the upper rod 38 will be locked against movement. As a result the spring 41 will be compressed between the upper end of cylinder 37 and head 39, the period of compression of said spring corresponding to approximately one-half the lowering stroke of the cylinder, or one-fourth of a complete operating cycle. During compression of spring 41, spring 40 is unaffected. If the above conditions are reversed, *i. e.*, when the left-hand channel is packed while the right channel is still receiving fuel, the spring 40 will be compressed on the up-stroke, and a normal down-stroke of the connections will be permitted. When both channels are packed, operation of the shaft 34 will alternately compress the two springs 40, 41. It will be noted that the crank 35 is at one-half its throw, when the sweep 28 is in vertical pendent position, so that the springs can be placed under tension or compressed during only one-half of a stroke in either direction, the other half of the stroke being consumed in returning the sweep to normal pendent position from an extreme position on either side.

The lower dead plate 19 of each grate extends down to the fuel-receiving end of its respective grate, and each dead plate is preferably supported by the triangular bearing members 20 at an inclination corresponding substantially to the inclination of the grate. In the embodiment illustrated in Figs. 1 to 9, inclusive, power operated rams are employed and thus the upper portion 19^a of the dead plate lies in a plane below the plane of the grate to provide a depressed channel in which the ram reciprocates, while the lower portion 19^b of the dead plate is flush with the fuel-bearing surface of the

120

125

130

grate. At its lower end, each dead plate 19 extends through a transverse slot 24^a in the inner wall 24, the upper edge of the slot 24^a being somewhat above the plane of the dead plate 19 but sufficiently low to cause the formation of a ridge of fuel behind the wall 24, for purposes which will presently appear. The upper end of the dead plate extends through a transverse slot 17^a in the front wall of the furnace and mounted on said upper end is a ram cover 42, the upper face of which is preferably flush with the lower portion 19^b of the dead plate and consequently flush with the fuel bearing surface 15 of the grate 2. Preferably the upper edge of the slot 17^a is located above the plane of the ram cover 42, whereby a hand tool may be readily inserted to force the fuel from the channel clear down to the lower end of the 20 grate to meet the needs of the fire there.

The ram works beneath the cover 42, and the ram and cover construction, with the means for operating the ram will now be set forth. Referring particularly to Figs. 5 to 25 9, inclusive, it will be noted that each ram is of a plate-like formation and the lower end of a ram 43 is divided by slots 43^a into separate divisions, there being in the present instance two slots which divide the ram into 30 three divisions 43^b. These slots are for the purpose of receiving dependent flanges 42^a formed on the under side of a ram cover 42, the flanges 42^a resting on the upper surface of the dead plate and thus, the cover 42 is 35 efficiently supported above the ram and prevented from falling down on the ram so as to interfere with its movement. As shown in Fig. 6 the surface of the ram on each side of the slot is downwardly curved, this being 40 indicated by the reference numeral 43^c, and the lower edge of the cover adjacent the flanges 42^a is similarly curved as at 42^b. Thus, the surface of the ram at these points will be cleaned, every time the ram is 45 retracted. It will be understood, however, that the curved edges 42^b must clear the curved surfaces of the ram so as not to interfere with movements of the latter. On its under side each ram is provided with racks 50 43^a which are engaged by the teeth of gear segments 44 fixed to a rock shaft 45. The rock shaft 45 is journaled in bearings extending outwardly from the front wall 17 of the furnace. Said shaft is provided with a 55 crank 46 which is pivoted to the upper end of a connecting rod 47. The latter is in turn pivoted at its lower end to a crank 48 on the main power shaft 34, whereby motion is transmitted to the gear segments 44 to reciprocate the ram and push the fuel in a 60 channel 16 down to the grate below. Preferably, the connecting rod 47 is made adjustable as shown in Fig. 2, whereby the throw of the crank 46 may be varied to 65 change the extent of movement of the ram.

The dividing pier 18 rests on the center plate 21 and is prevented from slipping by a stop 49 mounted on plate 21 which fits into a recess in the bottom of said pier. Secured to the inner wall 24 and extending therealong on each side of the dividing pier 18 are angle bracket plates 50, which support fire brick sections 51, the latter bridging the spaces on each side of the dividing pier between the side walls of the furnace and the pier. The faces of these firebrick sections serve to protect the metal of the inner wall from the heat of the combustion chamber.

Above the upper dead plate 23 on each side of the division plates 27, the front of 80 the furnace is recessed, as shown. Journaled in bearings formed in these division plates 27 and the end vertical plates 52 (see Fig. 3) are the outer and inner carrying-ears 53, 54 which together support the metal 85 frames 55 of the fire doors. There is a fire door on each side of the fuel-chute, as shown in Figs. 1 and 3, both of which are the same in construction. The frame 55 of a fire door supports a segmental section 56 of brick 90 or other refractory material, the latter when closed filling the opening 57 through which the combustion chamber may be opened to the outside. The rear face of the brick lining 56 is curved, as shown in Fig. 2 and at 95 its upper edge meets a curved extension or blade 58, the latter being adapted to engage a vertical plate 59 supported in a slot formed in an extension of the angular front wall 60. The wall 60 forms the front 100 inclosing member for a chamber 61 which receives preheated air from any suitable source by a pipe 62 which air is adapted to pass into the combustion chamber through a narrow passageway 63 between the rear face 105 of the fire door and the curved insulated wall 64. The fire doors may be opened and closed by counterweighted lever arms 65 secured respectively to the spindle portions of the outer ears 53.

The fire brick sections 51 form a protection for the iron work of the channel, and also partly for the iron work of the fire doors, as these sections contact with the lower edge of the fire doors when the latter 115 are closed, as shown in Fig. 2. Further protection for the iron work is afforded by reason of the fact that the air chamber 61 is constantly sending a current of air down over the rear face of the fire doors, thereby 120 preventing the brick of the fire-doors from getting very hot. In addition there will always be a thin film of air from the outside that will pass into the furnace between the lower iron edge of the fire doors and 125 the sections 51 of brick, so that these points of contact will not be overheated.

For shutting off the fuel from the channels, the chute is provided with a curved plate or gate 66 pivoted at the points 67. The gate 130

66 is provided with a hook 68 on its front face adapted to be engaged by a catch 69 which when so engaged serves to keep the gate elevated and the chute open. When 5 the catch 69 is released the gate 66 will descend by gravity to close the chute. The movement of fuel through the chute may be further controlled by a gate 70 located above the gate 66 and adapted to be operated 10 by a hand lever 71.

In the operation of the furnace, the fuel descends in the chute and is spread along into the channels 16 by the sweep 28. The rams working in the depressions in the lower 15 dead plates catch the fuel in the channels and push a part of it down to the grates below, while turning another part of the fuel upwardly into a ridge located just above the fuel-receiving ends of the respective 20 grates, letting the fuel in the ridges coke. When the lower portions of the grate are in need of fuel, hand tools may be passed into the openings 17^a over the ram covers which are flush with the upper surface of 25 the grate, and the fuel from these ridges rammed directly down the incline of the grate. It will be noted that all the fuel passes beneath the upper dead plate 23 and that therefore no obstruction is present 30 which would interfere with access to the fire through the openings behind the fire doors, when it becomes necessary to stir the fire.

In the form illustrated in Fig. 10, the 35 furnace is intended exclusively for hand stoking, the lower dead plate 72 being flush with the fuel bearing surface of the grate throughout its entire extent. The ramming tools will be inserted through the openings 40 in the front wall of the furnace, as heretofore described. A hand operated sweep 73 is also illustrated in connection with the furnace illustrated in Fig. 10. The other features of the furnace are the same substantially as those illustrated in Figs. 1 to 45 9, inclusive. For some varieties of bituminous coal it may be necessary to have the lower dead plate flush with the fuel bearing surface of the grate, throughout the extent 50 of said dead plate, as shown in Fig. 10, even when power rams are employed. The use or depth of the depressions in the dead plate can best be determined by practice and the character of the fuel.

55 In the case of an extra wide furnace which may have a single wide combustion chamber or several combustion chambers arranged one after the other in a long row and separated by the usual parting walls, 60 the inclosed fuel receiving channel may extend along in front of the single wide combustion chamber, or all the way along in front of several combustion chambers, in the same manner as illustrated in Figs. 2 65 and 4, and the fuel pushed down to the

grate by rams working in the single combustion chamber or those portions of the channel in front of the several combustion chambers. With a very long channel, however, it would be difficult to distribute the 70 fuel properly transversely in the channel, if the channel be supplied by a single chute and the fuel distributed by a single sweep working beneath the discharge end of the chute. This difficulty may be obviated in 75 an extra wide furnace by supplying the fuel receiving channel in front of the combustion chambers from a number of coal chutes instead of a single chute, the number of chutes being determined by the length of 80 the channel and the width of the grate surface supplied with fuel from the channel. A preferred arrangement for an extra wide 85 furnace is illustrated in Fig. 11, wherein several chutes are employed and the operation of the sweeps working beneath the chutes for distributing the fuel transversely is effected by connection with the toothed segments 30. Two chutes are shown in Fig. 11, although it will be understood that the 90 number of chutes may be increased as practice and the width of the furnace requires, the second chute 26^a being similar to chute 26 and located between vertical division plates in exactly the same manner, as shown 95 in Fig. 4. A sweep 28^a similar to sweep 28 is pivoted beneath the discharge end of the chute 26^a on a pivot pin 29^a. The sweep 28^a is oscillated to distribute the fuel transversely in the channel in unison with sweep 100 28 by the rod 74 having pivoted at its opposite ends links 75, 76, which links are respectively pivoted to the pins 29, 29^a.

What is claimed is:—

1. A furnace construction comprising the 105 combustion chamber, the grate supported within the combustion chamber, a substantially inclosed fuel receiving channel within the furnace extending transversely substantially clear across and in front of the fuel 110 receiving end of the grate, said channel having a transversely extending opening in its front and rear walls substantially coextensive with the latter, means for feeding fuel into said channel, and means for distributing 115 the fuel transversely therein, said distributing means and the openings in the walls of the channel being located in different horizontal planes, whereby access may be had to the interior of the combustion 120 chamber through the openings in the channel walls throughout the entire length of said channel.

2. A furnace construction comprising the 125 combustion chamber, the grate supported within the combustion chamber, a substantially inclosed fuel receiving channel within the furnace extending transversely substantially clear across and in front of the fuel receiving end of the grate, said channel hav- 130

- ing a transversely extending opening in its front and rear walls substantially coextensive with the latter, a means for feeding fuel into said channel located centrally between the opposite ends of the latter, and means for distributing the fuel transversely in said channel on each side of said feeding means, said distributing means and the openings in the walls of the channel being located in different horizontal planes, whereby access may be had to the interior of the combustion chamber through the openings in the channel walls throughout the entire length of said channel.
3. A furnace construction comprising the combustion chamber, the grate supported in an inclined position within said combustion chamber, a substantially inclosed fuel receiving channel within the furnace extending substantially clear across in front of the upper end of the grate, said channel having a transversely extending opening in its front and rear walls substantially coextensive with the latter, means for feeding fuel into said channel, and means for distributing the fuel transversely therein, said distributing means and the openings in the walls of the channel being located in different horizontal planes, whereby access may be had to the interior of the combustion chamber through the openings in the channel walls throughout the entire length of said channel.
4. A furnace construction comprising the combustion chamber, the grate supported in an inclined position within said combustion chamber, a substantially inclosed fuel receiving channel within the furnace extending substantially clear across in front of the upper end of the grate, said channel having a transversely extending opening in its front and rear walls substantially coextensive with the latter, a fire door in the furnace wall located above the channel, means for feeding fuel into said channel, and means for distributing the fuel transversely therein.
5. A furnace construction comprising the combustion chamber, the grate supported in an inclined position within said combustion chamber, a fuel receiving channel located behind the front wall of the furnace and extending substantially clear across in front of the upper end of the grate, said channel having a transversely extending opening in its front and rear walls substantially coextensive with said walls and substantially in alignment with the fuel supporting surface of the grate, fire doors in the front furnace wall located above the fuel receiving channel, means intermediate said fire doors for feeding fuel into said channel and means for distributing the fuel transversely in the channel.
6. A furnace construction comprising the combustion chamber, the grate supported in an inclined position within said combustion, a fuel receiving channel located behind the front wall of the furnace and extending substantially clear across in front of the upper end of the grate, said channel having a transversely extending opening in its front and rear walls substantially coextensive with said walls and substantially in alignment with the fuel supporting surface of the grate, fire doors in the front furnace wall located above the fuel receiving channel, means intermediate said fire doors for feeding fuel into said channel, means for distributing the fuel transversely therein, and a ram working within the channel for pushing fuel from the same down on to the grate.
7. A furnace construction comprising the combustion chamber, the grate supported within the combustion chamber, a substantially inclosed fuel receiving channel within the furnace extending transversely substantially clear across and in front of the fuel receiving end of the grate, said channel having a transversely extending opening in its front and rear walls substantially coextensive with the latter, a fire door located in the furnace wall above the fuel receiving channel, means located on one side of the fire door for feeding fuel into said channel, and means for distributing the fuel transversely therein.
8. A furnace construction comprising the combustion chamber, the grate supported within the combustion chamber, a substantially inclosed fuel receiving channel within the furnace extending transversely substantially clear across and in front of the fuel receiving end of the grate, said channel having a transversely extending opening in its front and rear walls substantially coextensive with the latter, means for feeding fuel into said channel, means for distributing the fuel transversely therein, and means for pushing the fuel from the channel on to the grate, said distributing means and the openings in the walls of the channel being located in different horizontal planes, whereby access may be had to the interior of the combustion chamber through the openings in the channel walls throughout the entire length of said channel.
9. A furnace construction comprising the combustion chamber, the grate supported in an inclined position within the combustion chamber, a substantially inclosed fuel receiving channel within the furnace extending transversely substantially clear across and in front of the upper end of the grate, the bottom of the channel being inclined toward the grate, and the front and rear walls of said channel each having an opening extending transversely substantially throughout their length, said openings be-

ing substantially in alinement with the fuel supporting surface of the grate, means for feeding fuel into said channel, means for distributing the fuel transversely therein, 5 and a ram working within the channel for pushing the fuel from the channel on to the grate, said distributing means and the openings in the walls of the channel being located in different horizontal planes, 10 whereby access may be had to the interior of the combustion chamber through the openings in the channel walls throughout the entire length of said channel.

10. A furnace construction comprising the combustion chamber, the grate supported within the combustion chamber, a fuel receiving channel extending substantially clear across in front of the fuel receiving end of the grate, said channel being located between the 15 front furnace wall and an inner wall, a firebrick section supported on the rear face of the inner wall and extending substantially the length of the channel, a fire door pivoted above the channel and with its lower edge 20 resting on the firebrick section, when the door is in closed position, means for feeding fuel into said channel, and means for distributing the fuel transversely in the channel. 25

30 11. A furnace construction comprising the combustion chamber, the grate supported within the combustion chamber, a fuel receiving channel extending substantially clear across the front of the fuel receiving end of the 35 grate, said channel located between the front furnace wall and an inner wall, a firebrick section supported on the rear face of the inner wall and extending substantially the length of the channel, a fire door pivoted above the channel comprising a 40 metallic frame and a rear firebrick section supported by said metallic frame, the metal of said fire door resting on the firebrick section of the inner wall when the door is in 45 closed position, means for feeding fuel into said channel, and means for distributing the fuel transversely in the channel.

12. A furnace construction comprising the combustion chamber, the grate supported within the combustion chamber, a substantially inclosed fuel receiving channel within the furnace extending transversely substantially clear across and in front of the fuel receiving end of the grate, 55 a chute for depositing fuel at one end of the channel, a pivoted sweep for pushing fuel deposited by the chute into said channel, a power shaft, and yielding connections between said power shaft and the sweep for 60 operating the latter.

13. A furnace construction comprising the combustion chamber, the grate supported within the combustion chamber, a substantially inclosed fuel receiving channel within the furnace extending trans-

versely substantially clear across and in front of the fuel receiving end of the grate, a chute for deposited fuel at one end of the channel, a pivoted sweep for pushing fuel deposited by the chute into said channel, a power shaft, and connections between the power shaft and the sweep for operating the latter, said connections including a spring yieldable under pressure of the fuel on the sweep. 75

14. A furnace construction comprising the combustion chamber, a chute, a fuel-receiving channel on each side of the chute from which fuel is fed into the combustion chamber, a pivoted sweep beneath the chute for pushing fuel alternately into said channels, a power shaft and sweep-operating connections yieldable under pressure of fuel packed in said channels on either or both sides of the sweep and interposed between 85 said power shaft and the sweep, whereby the power shaft is free to rotate when the sweep is prevented from moving by the packing of fuel on both sides of the sweep.

15. A furnace construction comprising the combustion chamber, a chute, a fuel receiving channel on each side of the chute from which fuel is fed into the combustion chamber, a pivoted sweep beneath the chute for pushing fuel alternately into said channels, 90 a power shaft, and connections between said power shaft and the sweep for swinging the latter, said connections including a pair of springs, one yieldable under pressure of fuel packed in a channel on one side of the 100 sweep and the other yieldable under pressure of fuel packed in the channel on the other side of the sweep, whereby the power shaft is free to rotate when the sweep is prevented from moving by the packing of 105 fuel on both sides of the sweep.

16. A furnace construction comprising the combustion chamber, a chute, a fuel-receiving channel on each side of the chute from which fuel is fed into the combustion chamber, a pivoted sweep beneath the chute for pushing fuel alternately into said channels, 110 said sweep being spaced from the bottom of said channels, a power shaft, and connections between said power shaft and the sweep for swinging the latter, said connections including a pair of springs compressible independently of each other, one spring yieldable under pressure of fuel packed on one side of the sweep and the other spring 115 yieldable under pressure of fuel packed on the other side of the sweep, whereby the power shaft is free to rotate when the sweep is prevented from moving by the packing of 120 fuel on both sides of the sweep.

17. A furnace construction comprising the combustion chamber, the grate, a fuel receiving channel from which fuel is fed into the combustion chamber, said channel including a fuel supporting surface located 130

in front of the grate, a ram for pushing fuel on to the grate embodying a plate adapted to be reciprocated over said fuel supporting surface, said ram having longitudinally extending slots, and a cover plate mounted over said ram having vertical depending flanges resting on the fuel-supporting surface of the channel and received within the slots of the ram.

18. A furnace construction comprising the combustion chamber, the grate, a fuel-receiving channel from which fuel is fed into the combustion chamber, said channel including a fuel supporting surface located in front of the grate, a ram for pushing fuel on to the grate embodying a plate adapted to be reciprocated over said fuel-supporting surface, said plate having slots extending longitudinally from its inner edge, the upper surface of the plate being downwardly curved along the sides of the slots, and a cover plate mounted over the ram having vertical depending flanges resting on the fuel supporting surface of the channel and received within the slots of the ram, said cover plate having transverse curved webs above the curved portions of the ram.

19. A furnace construction comprising the combustion chamber, the grate supported within the combustion chamber, a substantially inclosed fuel receiving channel within the furnace extending transversely substantially clear across and in front of the fuel receiving end of the entire grate surface of the furnace, a plurality of chutes arranged at intervals along said channel for depositing fuel in the channel, pivoted sweeps working beneath the discharge ends of the chutes for pushing fuel deposited by the chutes transversely into the channel, and means for oscillating said sweeps in unison.

20. A furnace construction comprising the combustion chamber, the grate supported within the combustion chamber, a substantially inclosed fuel receiving channel within

the furnace extending transversely substantially clear across and in front of the fuel receiving end of the entire grate surface of the furnace, a plurality of chutes arranged at intervals along said channel for depositing fuel in the channel, pivoted sweeps working beneath the discharge ends of the chutes for pushing fuel deposited by the chutes transversely into the channel, and a single power shaft and connections between said power shaft and the sweeps.

21. A furnace construction comprising the combustion chamber, the grate supported within the chamber, a fuel receiving channel in the front wall of the furnace extending transversely substantially clear across and in front of the fuel receiving end of the grate, a chute for depositing fuel in the channel, means for distributing the fuel transversely in the channel, a power shaft, and connections between the power shaft and distributing means for operating the latter, said connections including a spring yieldable under pressure of the fuel on the fuel distributing means.

22. A furnace construction comprising the combustion chamber, the grate supported within the chamber, a fuel receiving channel in the front wall of the furnace extending transversely substantially clear across and in front of the fuel receiving end of the grate, the front and rear walls of the channel having openings therein extending transversely throughout substantially their entire length, a chute for depositing fuel in the channel, a sweep for pushing fuel deposited by the chute into said channel, said sweep being spaced from the bottom of the channel and positioned above the transverse openings in the walls of the latter, whereby access may be had to the combustion chamber through the openings in the channel walls throughout the entire breadth of the furnace, and means for actuating said sweep.
